HIS ATTORNEY IN FACT

UNITED STATES PATENT OFFICE.

ALEXANDER T. KASLEY, OF SWISSVALE, PENNSYLVANIA.

POWER-DEVELOPING APPARATUS.

1,427,108.

Specification of Letters Patent. Patented Aug. 29, 1922.

Application filed May 8, 1918. Serial No. 233,330.

To all whom it may concern:

Be it known that I, ALEXANDER T. KASLEY, a citizen of the United States, and a resident of Swissvale, in the county of Allegheny and 5 State of Pennsylvania, have made a new and useful Invention in Power-Developing Apparatus, of which the following is a specification.

An object of this invention is to produce a 10 heat engine of high efficiency.

A further object is to produce an organized apparatus including a multi-stage elastic fluid turbine of any type and a displacer chamber in which means are employed for so utilizing the motive fluid delivered to the turbine that efficiency of the 15 entire apparatus is increased above that of similar power developing apparatus now in use and known to me.

20 A further object is to produce a power developing apparatus including a compound engine, in which means are employed for applying all the heat, employed in the organized apparatus at a temperature considerably above the boiling point of the fluid 25 corresponding to the highest pressure employed.

These and other objects, which will be 30 made apparent throughout the further description of my invention are accomplished by means of apparatus diagrammatically illustrated in the single sheet drawing accompanying and forming a part hereof.

In the drawing I have diagrammatically 35 illustrated one form of apparatus embodying my invention.

The apparatus illustrated includes a turbine 3 of any type employing multiple stages. As illustrated, the turbine is provided with 40 an inlet port 4, which communicates with a high pressure reservoir 5, and which delivers motive fluid to the high pressure blades or working elements of the turbine. The turbine is also provided with a delivery 45 port 6 located intermediate the inlet port 4, and an exhaust port 7. The port 6 communicates by a suitable passage, with a displacer chamber 9. The exhaust port of the turbine communicates with the atmosphere 50 or with a condenser.

The displacer chamber 9 contains a displacer 10 mounted on a rod 11, which projects through the wall of the chamber. As 55 illustrated, this displacer is provided with a downwardly projecting flange 12 which extends into an annular liquid seal 13, adapt-

ed to be supplied with sealing liquid from any suitable source. The displacer is capable of being reciprocated by any suitable means, such for example, as a lever 14 and 60 actuating mechanism 15. This mechanism may be driven by the turbine, or it may be driven independently by a separate motor. Above the displacer is a solid partition 16 which separates the displacer chamber 9 65 from the regenerator 17 and also compels fluid entering the chamber 9 from the regenerator to traverse heating tubes 18, which are subjected to the sensible heat of combustion in a furnace, diagrammatically illustrated at 19. The regenerator 17 also communicates with a passage 20 with which the passage 8 communicates by means of a check valve 21. The displacer chamber 9, the displacer 10, the regenerator 17, and the heating elements 18 are similar in the functions 70 and mode of operation to similar apparatus usually employed in well known hot air engines, and for simplicity may be termed regenerative apparatus. The passage 20 75 also communicates with the reservoir 5 by a check valve 22 and with the displacer chamber 9 below the displacer 10. A passage 24 is also provided which communicates with the chamber 9 above the displacer 10 and 80 with the receiving chamber 5 through the check valve 25. Feed water is supplied to the chamber 9 below the displacer 10 through a spray nozzle 26, which is shown controlled by a suitable valve 27. The liquid supplied 85 to the seal 13 is preferably cylinder oil or some such liquid which will not evaporate rapidly at the temperatures encountered. If, however, it is desirable to supply this seal with other liquid, such as water, it 90 may communicate with a source of constant supply. As illustrated, the furnace 19 is provided with a grate 28 located below the tubes 18 and a stack 29 which receives the products of combustion after they have 100 given up heat to the tubes 18.

The operation of the apparatus is as follows: In starting the apparatus, the displacer is first started in its reciprocatory motion, it being understood that the furnace 19 105 has previously been started. Assuming that the displacer is at the upper end of its stroke, its next movement will be downward, during which it displaces the fluid in the lower end of the chamber 9 and causes it to move 110 through the passage 20, regenerator 17, the tubes 18 and finally to enter the upper end of

the displacer chamber 9. During this portion of the cycle the fluid traversing the tubes 18 is subjected to furnace temperatures and consequently its temperature and pressure 5 will be increased until it exceeds the pressure in reservoir 5. As soon as the pressure in the reservoir 5 is exceeded, fluid will be delivered through the passage 24 and the check valve 25 and also from the passage 20 10 through the check valve 22 into the receiver, it being understood that both of these check valves operate inwardly with relation to the receiver and prevent a discharge of fluid through them from the receiver.

15 During the next portion of the cycle of the apparatus, the displacer 10 moves from the lower extremity of its stroke upwardly. While this is taking place, the fluid contained within the upper end of the chamber 9 is 20 forced out through the tubes 18, the regenerator 17, the passage 20 and finally into the space below the displacer 10. The fluid leaving the upper end of the displacer 9 gives up a large percentage of its heat to the 25 regenerator 17, and consequently is delivered to the lower end of the chamber 9 at a reduced temperature. The temperature of the fluid is thereupon further reduced by the water spray delivered through the nozzle 26, 30 and the water is evaporated into steam. Water is preferably delivered through the nozzle only during this portion of the cycle, although the apparatus will operate if a continuous flow of water is delivered. The 35 reduction in temperature occasions a drop in fluid pressure, because the specific heat of steam is materially less than the latent heat. This reduction in pressure is felt throughout the system above the check valves 21, 22 and 40 25. When the pressure has dropped below the pressure maintained at the port 6 of the turbine, the check valve 21 will open and the turbine will thereupon deliver fluid from the port 6 to the passage 20. This fluid 45 withdrawn from the turbine is during the cycle of the apparatus delivered again to the receiver 5 and consequently to the turbine.

In the operation of the apparatus the furnace or heat generating apparatus will be 50 controlled automatically or otherwise, in response to variations in the temperature within the upper part of chamber 9, and the supply of water through the nozzle 26 will be controlled automatically or otherwise in 55 response to variations in the pressure within the system above the check valves 21, 22 and 25.

It is well known that it is impossible to 60 construct boilers capable of generating steam at the highest permissible temperatures. This apparatus enables the efficient use of heat at these temperatures. For example, the temperature of the fluid delivered to the upper end of the chamber 9 may be approximately 65 700 degrees, whereas the temperature

conforming to the pressure in the chamber 5 would be approximately 350 degrees. Super-heating as ordinarily practiced enables a small part of the heat to be applied at these high temperatures, while my invention enables all of the heat to be applied at high 70 temperatures.

The operation of the apparatus has an analogy in the electric transformer in which an increased current at low voltage is derived 75 from a small current of high voltage. In the apparatus embodying my invention, the highest temperature in the turbine is considerably lower than the temperature supplied to the apparatus, and consequently the 80 quantity of fluid passing through at least a part of the turbine is materially increased. This increase in fluid is accomplished by withdrawing a portion of the fluid traversing a low pressure stage of the turbine and 85 returning it to the high pressure stage of the turbine. The thermodynamic gain, thereby accomplished, results from the fact that a large portion of the latent heat of the fluid is returned to the turbine without being lost 90 in the condenser or in the turbine discharge.

All of the water delivered through the nozzle 26 is vaporized by the superheated fluid to which it is subjected. This large volume of fluid is delivered at a moderate temperature to the receiver 5. The receiver, however, receives highly superheated fluid through the passage 24 and by suitably proportioning the valve areas the fluid delivered to the turbine can be kept at a desirable temperature considerably above that of dry 95 steam at the pressure of the receiver.

While I have described and illustrated but one embodiment of my invention, it will be apparent to those skilled in the art that 100 various changes, modifications, substitutions, additions and omissions may be made in the apparatus illustrated without departing from the spirit and scope of the invention, as set forth by the appended claims.

What I claim is:

1. In combination in a power developing apparatus, a compound engine, means for delivering motive fluid to said engine and means for periodically withdrawing a portion of the motive fluid from the working 115 passages of said engine after it has been partially expanded, and means for delivering heat to the fluid so withdrawn and for returning the fluid to the inlet of the engine. 120

2. In combination in a power developing apparatus, a compound engine, means for delivering superheated fluid to the inlet of engine and for periodically withdrawing 125 partially expanded fluid from a working passage of the engine, and means for delivering heat to the fluid so withdrawn and for returning the fluid to the inlet of the engine.

3. In combination in a power developing apparatus, an evaporating chamber, means 130

- for periodically forcing heated fluid into liquid for admixture with said fluid, a fluid actuated engine having communicating high and low pressure portions, and connections between the apparatus and the high pressure portion whereby the high pressure portion operates on the differences in pressures obtaining in said apparatus, a portion of the working fluid being returned to said apparatus after passage through the high pressure engine portion and a further portion of said working fluid passing through the low pressure engine portion. 50
5. In combination with a fluid actuated engine, a regenerative apparatus, comprising a heating chamber, a cooling chamber, a passage connecting said chambers, a displacer between said chambers for forcing fluid from one chamber into the other, 10 means for injecting cooling liquid into said cooling chamber, and means for delivering fluid generated in said chamber to said engine and for delivering fluid from said engine to said regenerator. 15
- 20 6. In combination with a fluid actuated engine, a regenerative apparatus, comprising a receiving chamber which communicates with the inlet of said engine, a displacer chamber, a passage connecting the ends of said displacer chamber, heat imparting means in said passage, a regenerator in said passage, a displacer within said chamber for causing a flow of fluid from one end to the other of said chamber, and a one way 25 valve between said passage and said receiver chamber.
- 30 7. In an apparatus of the character described, a chamber, a displacer located within said chamber, a passage communicating with both ends of said chamber, a source of heat in the path of travel of fluid entering one end of the chamber from said passage, means generating additional fluid under pressure by the heat of the fluid entering the other end of the chamber, and an engine receiving fluid from said passage. 75
- 35 8. In an apparatus of the character described, means for supplying heat to a confined fluid, means for abstracting and storing a portion of the heat so delivered, and means for generating fluid under pressure by forcing liquid into the partially cooled fluid and thereby generating additional 65 fluid. 9. In an apparatus of the character described, a chamber, a displacer located within said chamber, a passage communicating with both ends of said chamber, a source of 70 heat in the path of travel of fluid entering one end of the chamber from said passage, means generating additional fluid under pressure by the heat of the fluid entering the other end of the chamber, and an engine receiving fluid from said passage. 75
- 40 10. In an apparatus of the character described, a chamber, a displacer located within said chamber, a passage communicating with said chamber on opposite sides of said displacer, means for heating the fluid entering one end of the chamber, means for generating additional fluid by subjecting liquid to the heated fluid, and an engine receiving fluid from said passage. 85
- 45 7. In testimony whereof, I have hereunto subscribed my name this 31st day of October, 1917.
- ALEXANDER T. KASLEY.
